UNITED STATES PATENT OFFICE.

JACOB B. BLEICHRODE, OF NEW YORK, N. Y., ASSIGNOR TO J. B. BLEICHRODE & CO., OF NEW YORK, N. Y., A CORPORATION OF NEW YORK.

DESIGN FOR A HANGER FOR GARMENTS.

No. 38,255.

Specification for Design.

Patented Sept. 25, 1906.

Application filed June 22, 1905. Serial No. 266,515. Term of patent 3½ years.

To all whom it may concern:

Be it known that I, JACOB B. BLEICHRODE, a citizen of the United States, residing in the borough of Manhattan, city, county, and State of New York, have invented a new, original, and ornamental Design for a Hanger for Garments, of which the following is a specification.

Figure 1 of the accompanying drawings is a front elevation of a hanger, showing my new design; and Fig. 2 is a rear view thereof.

I claim—

The ornamental design for a hanger for garments as shown.

JACOB B. BLEICHRODE.
